UNITED STATES PATENT OFFICE.

GEORGE F. McDONNELL, OF CHARLESTON, AND JOHN JOSEPH DANDOY, OF DUNBAR,
WEST VIRGINIA.

DESIGN FOR A MILK-JAR.

55,068.

Specification for Design.

Patented May 4, 1920.

Application filed January 25, 1919. Serial No. 273,178. Term of patent 14 years.

To all whom it may concern:

Be it known that we, GEORGE F. McDONNELL and JOHN JOSEPH DANDOY, citizens of the United States, residing, respectively, at Charleston and at Dunbar, in the county of Kanawha and State of West Virginia, have jointly invented a new, original, and ornamental Design for Milk-Jars, of which the following is a specification, reference being had to the accompanying drawing, forming part thereof.

Our new, original and ornamental design

for a milk jar is shown in the accompanying drawing, in which,

The figure is a perspective view of a milk jar, showing our new design.

We claim:

The ornamental design for a milk jar, substantially as shown.

GEORGE F. McDONNELL.
JOHN JOSEPH DANDOY.
